DESIGN FOR A COOKING RANGE

Samuel Klute, South Bend, Ind., assignor to The Malleable Steel Range Manufacturing Company, South Bend, Ind.

Application February 6, 1935, Serial No. 55,265

Term of patent 7 years

To all whom it may concern:

Be it known that I, Samuel Klute, a citizen of the United States, residing at South Bend, in the county of St. Joseph, State of Indiana, have invented a new, original, and ornamental Design for a Cooking Range, of which the following is a specification, reference being had to the accompanying drawings, forming a part thereof.

Figure 1 is a perspective view of the cooking range embodying my invention.

Figure 2 is a view of the range in front elevation.

Figure 3 is a view of the range in side elevation.

I claim:

The ornamental design for a cooking range as shown.

SAMUEL KLUTE.
